CLAIM

The ornamental design for a ratchet wrench, as shown and described.

DESCRIPTION

FIG. 1 is a front elevational view of a first embodiment of a ratchet wrench showing my new design;

FIG. 2 is a rear elevational view thereof;

FIG. 3 is a right side elevational view, with the left side being a mirror image, thereof;

FIG. 4 is a top plan view thereof;

FIG. 5 is a bottom plan view thereof;

FIG. 6 is a perspective view thereof.

FIG. 7 is a front elevational view of a second embodiment of a ratchet wrench showing my new design;

FIG. 8 is a rear elevational view thereof;

FIG. 9 is a right side elevational view, with the left side being a mirror image, thereof;

FIG. 10 is a top plan view thereof;

FIG. 11 is a bottom plan view thereof; and,

FIG. 12 is a perspective view thereof.
